UNITED STATES PATENT OFFICE.

MAX HERSKOVITZ, OF CHICAGO, ILLINOIS; WILLIAM HERSKOVITZ AND CHARLES WEINFELD, EXECUTORS OF SAID MAX HERSKOVITZ, DECEASED, ASSIGNEES TO PEERLESS LIGHT COMPANY, OF CHICAGO, ILLINOIS, A CORPORATION OF MAINE.

ELECTRIC-LIGHTING FIXTURE AND LAMP SOCKET THEREFOR.

Application filed February 2, 1924. Serial No. 690,182.

This invention relates to electric lighting fixture and lamp socket therefor and its principal object is to simplify the construction of lighting fixture members, and 5 to minimize the cost of production thereof. Another object is to simplify the work of assembling the parts, and the wiring thereof and to otherwise improve thereon. With 10 these objects and advantages in view this invention consists in the several novel features of construction, arrangement and combination of parts, hereinafter fully set forth and claimed.

The invention is clearly illustrated in the 15 drawing accompanying this specification, in which:—

Fig. 1 is a side elevation of an electric lighting fixture embodying a simple form of the present invention, and a supporting member to which the fixture is secured; Fig. 2 is a central, vertical section there- 20 through; Fig. 3 is a central, vertical section through a slightly modified form of the invention and Fig. 4 is a central, vertical section through a second modified form of the invention.

Referring to said drawing and first to Figs. 1 and 2, the reference character 5 designates a bracket arm, in the form of 25 a single casting having a housing 6 at its upper end and a channel or passage 7 leading from the cavity 8 of the housing to its end 9. At said end 9, the arm is threaded internally and formed with barbs 10. In 30 the threaded end of the arm is secured a threaded nipple 11 and on said nipple is a nut 12. One of the uses of the present bracket is to illuminate mirrors, consoles, picture frames, beds and other articles and 35 the bracket is secured thereto by passing the nipple 11 through a hole 13 in the frame 14 and screwing the nut 12 up against the back of the frame, thereby clamping the frame between the end of the arm 5 and nut 12. The barbs 10, bite into the frame 40 and positively prevent the bracket from turning thereon.

Secured in the cavity or recess 8 of the housing 6, is an electric socket member 15 45 which has conductor cords 16, permanently secured to its contact pieces 17, 18. In wiring the bracket arm 5, the wires are inserted through the cavity 8, and pushed out through the end of the passage 7, and the

socket member is inserted into the cavity 8. 55 A set screw 6^a threaded in the wall of the housing 6, bears against the socket member 15 and secures it in place in the housing.

The socket member 15 may comprise the usual internal or interior members of a lamp socket, such as the threaded shell 17, and the center contact piece 18 secured to the porcelain support 19. The conductor cords 16, in this case, are soldered to the contact pieces and the contact pieces, porcelain support 60 and ends of the conductor cords are secured in a paper case 20 by cement or the like 21. These assembled interior parts of a lamp socket I shall designate as a "socket interior". This construction provides an ex- 65 ceedingly cheap, yet practical durable and approved socket.

Formerly in order to wire a fixture, in which the electric socket was contained in a housing it was necessary to have a nipple 75 on the inside of the housing and to use an electric socket made up of several separable parts, and the fixture would necessarily have to consist of several pieces. All of this was made necessary to avoid twisting the 80 wires when securing the electric socket in place in the housing. The labor and time required for assembling and wiring such fixtures, made the cost thereof more than twice that of the present fixture. 85

In the form shown in Fig. 3 a sheet metal housing 22 is shown, which has a contracted end portion 23 formed with an internal neck 24. The neck is internally threaded whereby the casing 22 may be secured upon a 90 threaded nipple 25 of a lighting fixture, and a set screw 26 is threaded in the reduced part 23 and arranged to impinge against said nipple 25. The interior 15 is secured in the casing 22 by a set screw 6^a as in the 95 preferred form.

In the form illustrated in Fig. 4 a housing 22^b and socket interior 15 of reduced size is shown attached to a threaded nipple 25^b, of a bracket or other fixture arm, and locked in 100 place by a set screw 26. This form of the invention is intended principally for use in connection with the candle type of light. In this case the casing 22^b is of much less diameter than the casing of the form shown in Fig. 3, and the contracted part is omitted, the inturned neck 24 being formed directly upon the lower end of the wall of the cas- 105

ing. Otherwise, the construction of the casing and lamp socket may be substantially the same as that illustrated in Fig. 3. The socket interior 15 is secured in the housing by a set screw 6^a as in the other forms shown. The screw 6^a holds the socket interior at any place in the housing and prevents it from turning therein. The screw 26 impinges against the nipple and prevents the housing from turning thereon. These screws are accessible from the exterior of the housing which makes it easier to secure the parts together.

The forms illustrated in Figs. 3 and 4 function in the same manner as those shown in Figs. 1 and 2, so far as the wiring is concerned, and in addition thereto this form may be assembled with standard forms of fixtures, brackets and the like, with the same ease as the form shown in Figs. 1 and 2.

More or less variation of the exact details of construction is possible without departing from the spirit of this invention; I desire, therefore, not to limit myself to the exact form of the construction shown and described, but intend, in the following claims, to point out all of the invention disclosed herein.

I claim as new, and desire to secure by Letters Patent:

In an electric lighting fixture, a housing in the form of a lamp socket casing, a yieldable paper case in said housing, a threaded shell and a center contact piece cemented into said paper case, conductor cords leading away from said shell and center contact piece, and a set screw threaded in the wall of said housing and impinging against said paper case.

MAX HERSKOVITZ.
